UNITED STATES PATENT OFFICE.

FRED G. NIECE, OF CLEVELAND, OHIO.

OZONIZER.

Application filed December 15, 1919, Serial No. 344,798. Renewed April 1, 1924.

To all whom it may concern:

Be it known that I, FRED G. NIECE, a citizen of the United States, and a resident of Cleveland, county of Cuyahoga, and State of Ohio, have invented a new and useful Improvement in Ozonizers, of which the following is a specification, the principle of the invention being herein explained and the best mode in which I have contemplated applying that principle, so as to distinguish it from other inventions.

The present improvements relate to that type of ozonizing apparatus wherein an electrical discharge through air or oxygen is utilized to produce the desired ozone. One object of the invention is the production of uniformly ozonized air, in contradistinction to a mixture of varying concentration. A further object is to render it possible to obtain and maintain a higher concentration than is possible with current commercial apparatus.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—

Fig. 1 is a central axial section of my improved apparatus; Fig. 2 is an elevational view of one of the stationary electrodes forming a feature of such apparatus; Fig. 3 is a similar view of one of the dielectric plates; and Fig. 4 is a similar view of a rotary electrode.

In the preferred form illustrated, the apparatus is shown as contained within a cylindrical chamber 1, which may be either horizontally disposed as illustrated, or vertically if desired. The air or oxygen to be treated is admitted to chamber 1 through a duct 2 adjacent one end, and the treated gas passes out through another duct 3 adjacent the other end. A cooling jacket 4 preferably surrounds chamber 1 having an inlet duct 5 and an outlet duct 6, whereby a cooling fluid such as water may be circulated in contact with the cylindrical wall of the chamber.

Extending axially of the chamber is a ro-

tatable shaft 7 which may be driven in any suitable way, but is preferably directly connected at one end with an electric motor 8, as shown in Fig. 1. The end in question is 60 preferably the intake end of the chamber, and the space occupied by the motor is separated from the remainder of the chamber by a partition 9 having a central opening that may be increased or decreased in size as desired, by means of a diaphragm shutter 10 or equivalent device. The air passing into the chamber from duct 2 accordingly passes over the motor in order to reach this opening in partition 9, and thereby assists in 70 keeping said motor cool.

Mounted upon, but insulated from, shaft 7 is a series of electrodes 12 spaced lengthwise of said shaft and alternating with a corresponding series of stationarily mounted electrodes 13. The latter have central openings 14 so as not to contact with the shaft, and are peripherally insulated as shown. Interposed in turn between each adjacent pair of electrodes 12 and 13 is a dielectric 80 plate 15, so that in the complete assemblage of parts, an electrode 12, rotatable with shaft 7, will be seen to lie between each pair of dielectric plates 15. The latter are provided with central openings 16 similar to the openings 14 in stationary electrodes 13, but preferably of smaller diameter.

The current is supplied by means of suitable leads 18 and 19 to the shaft 7 and the stationary electrodes 13, shaft 7 being connected by means of suitable insulated connections 20 with the respective rotating electrodes 12.

Having thus described the construction of my apparatus, the mode of operation of the same may be readily explained. The one set of electrodes, as already noted, is rotatable with shaft 7, by means of motor 8 connected with said shaft. The electric discharge accordingly passes through successive 100 electric plates from a stationary to a revolving electrode, or vice versa. The current of air passing through the chamber 1 is simultaneously drawn across the faces of the dielectric plates, first radially inwardly and 10: then radially outwardly, due to the arrangement of openings in said plates and the interposed stationary electrodes.

As a result, in the first place due to the revolving of the electrodes, any inequalities in 11: the thickness of the dielectric plates or the spacing of the electrodes is balanced up, thus

liminating variations in current density per unit of discharge surface. At the same time the air currents produced, as just stated, and by the revolving electrodes themselves, cause a thorough and even mixture of the air contained within the chamber, so that the ozonation is uniform throughout. The air currents in question produce a further advantageous result, in that the tendency of the dielectric plates to heat up and rupture is minimized, the heat evolved being radiated through the chamber wall and absorbed by the cooling medium in jacket 4. For low concentrations this jacket may be simply air-cooled, water being employed only for high concentrations of ozone.

By means of my improved apparatus I overcome the main difficulty heretofore encountered in obtaining and maintaining a relatively high concentration of ozone, for example five grams per cubic meter. The chief difficulty heretofore encountered has been the heating of the apparatus not only causing frequent rupture of the dielectrics, but, even worse, causing the ozone to break down immediately into oxygen again. Accordingly, the only satisfactory method heretofore of obtaining ozone of high concentration has been to ozone the air to a moderate concentration, then passing the resulting product through a chilling chamber, thereupon subjecting the same to a second treatment, and so on until the desired concentration is obtained. This obviously makes a high cost of production, whereas by my apparatus the successive stages of ozonation are accomplished in one operation, and directly from the original air or oxygen introduced into the apparatus.

The cooling of the air in the chamber has the desirable effect of causing most of the moisture therein to condense and precipitate, the outlet serving to withdraw the water of condensation. The air is thus rendered nearly dry as possible.

Other modes of applying the principle of my invention may be employed instead of the one explained, change being made as regards the mechanism herein disclosed, provided the means stated by any of the following claims or the equivalent of such means be employed.

I therefore particularly point out and distinctly claim as my invention:—

1. In an ozonizing apparatus, the combination of a closed chamber having supply and discharge ducts, whereby the air or oxygen being treated may be passed therethrough; a series of alternately spaced electric plates and discharge electrodes mounted in said chamber so as to be rotatable relatively to each other, each of said plates and every alternate electrode being centrally apertured to cause the air or

oxygen treated to flow over each side of said plates and suitable electrical connections to said electrodes.

2. In an ozonizing apparatus, the combination of a closed chamber having supply and discharge ducts, whereby the air or oxygen being treated may be passed therethrough; a cooling jacket surrounding said chamber; a series of alternately spaced dielectric plates and discharge electrodes mounted in said chamber, alternate electrodes mounted so as to be rotatable relatively to said plates; and suitable electrical connections to said electrodes.

3. In an ozonizing apparatus, the combination of a closed chamber having supply and discharge ducts, whereby the air or oxygen being treated may be passed therethrough; a partition having an opening of adjustable size at the air inlet end of said chamber; a cooling jacket surrounding said chamber; a series of alternately spaced dielectric plates and discharge electrodes mounted in said chamber, alternate electrodes mounted so as to be rotatable relatively to said plates; and suitable electrical connections to said electrodes.

4. In an ozonizing apparatus, the combination of a closed chamber having supply and discharge ducts, whereby the air or oxygen being treated may be passed therethrough; a series of spaced dielectric plates stationarily mounted in said chamber; a series of electrodes interposed between said plates, alternate electrodes being stationary and the others rotatable relatively to said plates; and suitable electrical connections to said electrodes.

5. In an ozonizing apparatus, the combination of a closed, approximately cylindrical chamber having supply and discharge ducts adjacent its respective ends, whereby the air or oxygen being treated may be passed through said chamber; a rotatable shaft axially mounted in said chamber; a motor at the supply end of the latter connected to rotate said shaft; a partition separating said motor from the remainder of said chamber, said partition having a central opening of adjustable size; a series of dielectric plates and discharge electrodes mounted in said chamber symmetrically about said shaft, certain of said series being carried by said shaft so as to rotate relatively to the others; and suitable electrical connections to said electrodes.

6. In an ozonizing apparatus, the combination of a closed, approximately cylindrical chamber having supply and discharge ducts adjacent its respective ends, whereby the air or oxygen being treated may be passed through said chamber; a rotatable shaft axially mounted in said chamber; a motor at the supply end of the latter connected to rotate said shaft; a partition

separating said motor from the remainder of said chamber, said partition having a central opening of adjustable size; a series of dielectric plates stationarily mounted 5 in said chamber symmetrically about said shaft; a series of electrodes interposed between said plates, alternate electrodes being stationary and the others being carried by said shaft so as to rotate therewith; and 10 suitable electrical connections to said electrodes.

7. In an apparatus of the character described, the combination of a series of spaced dielectric plates; a series of spaced

electrode plates adapted to be connected to 15 one terminal of an electrical source; a series of spaced electrode plates adapted to be connected to the other terminal of the electrical source; some of said plates being rotatable in relation to the remaining plates; all of said 20 plates being in substantially parallel relation, and each dielectric plate being arranged between and spaced from one of the first mentioned series of electrodes, and one of the second series of electrodes. 25

Signed by me, this 13th day of December, 1919.

FRED G. NIECE.
